UNITED STATES PATENT OFFICE.

MARK M. BUTLER, OF LOS ANGELES, CALIFORNIA.

DEVICE FOR SPREADING ASPHALTIC CONCRETE.

Application filed February 10, 1925. Serial No. 8,207.

To all whom it may concern:

Be it known that I, MARK M. BUTLER, a citizen of the United States, residing at Los Angeles, county of Los Angeles, and State of California, have invented a certain new and useful Device for Spreading Asphaltic Concrete, of which the following is a specification.

This invention relates to road building machinery and especially to devices for supplying surfacing materials to roadways in a continuous, even and automatic manner.

The invention is designed particularly to deposit a hot asphaltic concrete mix upon roadways and spread same evenly and continuously.

As now practiced, asphaltic concrete mixed in some central plant, is conveyed to the street or other point of deposit, where the contents of the conveyance are dumped. The load thus deposited is then shoveled and raked by hand labor to the depth required and desired. Owing to the difficulty and almost impossible work of obtaining a regular and even surface by hand raking and manual labor in general, road and roadways built on this plan, are uneven, undulating and irregular, and unable to sustain the wear of traffic and retain a desirable even surface.

The object of this invention therefore is to obviate this need of manual attention to the hot concrete mix deposited upon a road bed and to provide a simple and effective means for automatically spreading the prepared mix over a road bed in any desired thickness, evenly and expeditiously.

Other objects, advantages, and structural features for carrying into effect the purposes enumerated, will appear from the subjoined specification, in connection with the accompanying drawing, which illustrates a form of embodiment of the invention for carrying out the objects stated.

In the drawing,

Fig. 1 is a front view showing a form of device embodying the principle of the invention.

Fig. 2 is a rear view partly broken to illustrate parts otherwise hidden.

Fig. 3 is a side view and

Fig. 4 is a fragmentary rear view showing a means for heating and stirring the concrete mix.

The invention, as shown in a preferred form in the drawing, embodies a receiver 1, into which is arranged to be deposited the

asphaltic mix. The receiver 1 is provided with side walls 2, a rear wall 4 and a bottom 5, which inclines to the rear of the receiver and terminates in an apron 6, which as seen in Figs. 2, 3, and 4, extends below the rear wall 4 and side walls 2 of the receiver providing between such apron and rear wall 4, a longitudinally extending throat 7, the transverse area of which is arranged to be determined by a blade 8, which as pointed out presently is operable upon and relative to said rear wall 4. The rear wall 4 is inclined to the vertical and co-operates with the inclined bottom 5 in discharging the contents of the receiver.

The blade 8, referred to, is movable vertically relative to the bottom edge of the rear wall 4 of the receiver to regulate the extent of the throat and control the quantity of material discharging from the receiver. To effect this movement of the blade, I may provide such means as shown in Figs. 2 and 3, and consisting of means, as a crank 9 having threaded engagement with the rear wall 4 and swiveled to the blade 8, whereby upon turning the crank 9, the blade 8 will be operated in a vertical direction. Owing to the length of the blade 8, and the necessity for, at times, operating one end of same to greater extent than the other, for the purpose of causing a greater quantity of material to escape at one end than at the other, I have found it advisable to make provision whereby this operation of one end of the blade higher than the other may be readily accomplished, without binding. Such a provision may include members 10 secured to said blade 8 and operable in guides 11, which comprise each a pair of angle irons secured upon the rear wall 4 and disposed at an angle to each other. Thereby one end of the blade 8 may be readily elevated to greater extent than the other, for the purposes mentioned. The blade 8 may be provided with a means for increasing the width of the asphaltic deposit and for striking off the deposited material to the level desired.

Such a means is shown in Figs. 1, 2, and 3, as comprising a plate 12 mounted upon the blade 8 and laterally operable in suitable guides 13 relative to said blade. The strike off plate 12 may be provided with a rack 12' arranged for engagement by a pinion 12'' to operate the blade. The pinion 12'' is secured upon a crank 14 which is in convenient position for manual operation, from a plat-

form 15, which is hingedly mounted upon the rear of the receiver 1, and serves to form a convenient support for the operator during the traverse of the device over the ground.

- 5 As seen, the receiver 1 is mounted upon a frame structure 16, Fig. 3, over and beyond which the throat 7 of the receiver extends. The frame structure 16 is carried by and supported upon a forward roller 17 and a 10 rear roller 18, both rollers 17 and 18 journaled in said frame structure 16. The throat 7, of the receiver 1, is thus above the surface of the ground and the apron 6, in which the bottom of the receiver terminates, curves 15 downwardly over the rear roller 18, thereby protecting it from the concrete asphaltic mixture and serving to cause the contents of the receiver to flow evenly from the receiver in continuous manner.
- 20 Provision may also be made and included in the structure detailed herein for regulating the width of the deposit, that is, for causing the deposit to be made within limits narrower than defined by the normal 25 width of the structure. This may be accomplished by an arrangement as shown in Figs. 1 and 2 and consisting of partitions 19 movable relative to the throat 7, the side walls 2, and the rear wall 4. These partitions 19 are pivotally secured to said side walls 2 and the pivotal mount for each said partition may comprise, as shown, a rod 20 fastened to the forward edge of each partition and an eye bolt 21 through which said 30 rod 20 is extended. The eye bolt 21 of each partition 19 extends through rearwardly inclining slotways 22, in the side walls 2, and on said eye bolts are cam or other handles 23 provided to lock said partitions 35 19 in position after adjustment of same has been effected for the purposes mentioned; to wit, reducing the throat area in width in order to narrow the discharge of the asphaltic concrete. To resist displacement of the 40 rear ends of said partitions 19, I prefer to provide on each partition a stud 24 extending rearwardly beyond same and arranged to engage holes 25 in the rear wall 4, a number of such holes 25 being provided in practically a horizontal line and spaced to provide the adjustment necessary for width of 45 the discharge required.
- 50 It will be noticed that the slotways 22 in the side walls are parallel to the bottom 5, this construction being needed to insure a constant contact of the bottom of the partitions 19 with the bottom 5 of the receiver 1, and maintain the connection with the side walls.
- 55 55 When using hot asphaltic mixes, it may be desirable to keep the ingredients heated and in a state of motion to prevent setting. I have illustrated a form of device that may be conveniently applied to and removed from the receiver 1 without interfering with the

operation of the device, or necessitating any alteration. Such a provision is shown especially in Figs. 3 and 4, and may comprise a hollow shaft 26, provided with exterior stirring members or fingers 27. This hollow shaft 26 is arranged to be heated by a suitable burner 28, supplied with fuel from a tank 29, fastened onto the outside of one of the side walls 2. By chain and gear mechanism, generally shown at 30, power is derived from the rear roller 18 to revolve said shaft 26 and stir the asphaltic mixture. It will be obvious that the partitions 19 are removed from the receiver, to accommodate the installation of the stirring and heating apparatus.

70 The rear wall 4 is reinforced and protected against bulging, buckling and undue strain from the load within by suitable brace rods 31, which are securely fastened to the bottom 5 and to said rear wall.

75 What I claim, is:

1. An apparatus for spreading hot materials comprising a receiver for the materials, having a rearwardly inclining bottom and a rear wall at an angle to the vertical, the bottom of said rear wall spaced from the bottom of said receiver to provide a discharge throat, means movable on said rear wall to control the transverse area of said throat, and rollers arranged in pairs supporting said receiver above the surface operated over.

80 100 105 110 115 120 125 An apparatus for spreading hot materials comprising a receiver for the materials, having a rearwardly inclining bottom and a rear wall spaced from said bottom and providing a throat for the discharge of the material, means on and movable relative to said rear wall to control the transverse area of said throat means on and movable relative to the side walls and said throat to control the width of said throat, strike off means for the material, said means laterally movable relative to said first named means, and rolling means supporting said receiver above and free of the ground.

ground and disposed forward of the throat in said receiver, a blade on said rear wall movable relative thereto and to the throat to control the transverse area of said throat, 5 means to operate said blade, partitions connected with said receiver and movable relative thereto and to said throat to control the width of the throat, a strike-off plate on and movable with and relative to said 10 blade, and means to operate said strike-off plate.

5. An apparatus for spreading road materials comprising a receiver for the material having a discharge throat in the rear thereof, a means to regulate the transverse area of said throat to control the depth of material laid, adjustable means within said receiver to regulate the width of the throat to control the width of the material laid, and 15 means to lock said adjustable means in position of adjustment.

6. An apparatus for spreading road materials comprising a receiver for the materials having a discharge throat in the rear thereof, a blade movable on said receiver to control the transverse area of said throat, means to operate said blade, and means on said blade forming extensions of same to control the deposit of the material beyond the normal limits of the apparatus, and comprising 20 plates having wings forming end walls for the throat, and means to operate said plates relative to said blade.

7. An apparatus for spreading hot road materials comprising a receiver having a rear discharge throat, roller means supporting said receiver entirely above the ground, a blade to control the transverse area of the throat to regulate the depth of the material laid, plates on said blade forming extensions thereof to control the deposit of the material beyond the normal limits of the apparatus, means to agitate said material, and means to heat said agitating means.

8. An apparatus for spreading hot road materials comprising a receiver having a rear discharge throat, roller means supporting said receiver entirely above the ground, a blade to control the transverse area of the throat to regulate the depth of the material laid, means to operate said blade, plates on said blade forming extensions thereof to control the deposit of material beyond the normal limits of the apparatus, means to operate said plates relative to said blade, and a platform on said apparatus and extending longitudinally of the same and above the surface of the material laid.

9. An apparatus for spreading hot materials comprising a receiver for the materials, having a rearwardly inclining bottom and a rear wall at an angle to the vertical, the bottom of said rear wall spaced from the bottom of said receiver to provide a discharge throat, means on and movable relative to said rear wall to control the transverse area of said throat, and selective means to control the deposit of material through said throat beyond the sides of the apparatus.

10. An apparatus for spreading hot materials comprising a receiver for the materials having a rearwardly inclining bottom and a rear wall spaced from the bottom of said receiver to provide a discharge throat, and means to heat the material in said receiver.

11. An apparatus for spreading hot materials comprising a receiver for the materials, having a rearwardly inclining bottom and a rear wall spaced from said bottom and providing a throat for the discharge of the material, means on and movable relative to said rear wall to control the transverse area of said throat and means movable relative to the side walls and said throat to control the width of said throat.

12. An apparatus for spreading hot materials comprising a receiver having a rearwardly inclining bottom, and a rear wall spaced from said bottom to provide a throat, means movable on said rear wall to control the transverse area of said throat, means movable relative to the side walls to control the width of the throat, roller means supporting said receiver above the ground and disposed free of the throat in said receiver, and strike-off means on and movable with and laterally to said control means.

13. An apparatus for spreading hot materials comprising a receiver having a rearwardly inclining bottom, and a rear wall spaced from said bottom to provide a throat, means movable on said rear wall to control the transverse area of said throat, means movable relative to the side walls to control the width of the throat, roller means supporting said receiver above the ground and disposed free of the throat in said receiver, and strike-off means on said control means.

14. An apparatus for spreading road materials comprising a receiver for the material having a discharge throat in the rear thereof, a means to regulate the transverse area of said throat to control the depth of material laid, and means within said receiver to regulate the width of the throat to control the width of the material laid, and means to control the deposit of material through said throat beyond the sides of the apparatus.

15. An apparatus for spreading road materials comprising a receiver for the material having a discharge throat in the rear thereof, means to regulate the transverse area of the throat to control the depth of material laid, means to regulate the longitudinal area of the throat to control the width of the material laid, roller means supporting the receiver above the ground and

means laterally movable relative to the receiver to strike off deposited material.

16. An apparatus for spreading hot materials comprising a receiver having a discharge throat in the rear thereof, a blade to regulate the transverse area of said throat to control the depth of material laid, roller means supporting said receiver above the ground and free of the throat therein, and means on and laterally movable relatively to said blades to strike off deposited material.

17. An apparatus for spreading hot materials comprising a receiver having a discharge throat in the rear thereof, a means to regulate the transverse area of said throat to control the depth of material laid, roller means supporting said receiver entirely above the surface operated over, means to heat the material, and a platform longitudinally of said receiver and above the surface of the material laid.

18. An apparatus for spreading hot materials comprising a receiver having a dis-

charge opening therein, a means to regulate the transverse area of said opening to control the depth of material laid, and means on said receiver to strike off deposited material.

19. An apparatus for spreading road materials comprising a receiver having a discharge opening therein, a means to regulate the transverse area of said opening to control the depth of material laid, and a platform longitudinally of the receiver and above the surface of the material laid.

20. An apparatus for spreading hot materials comprising a receiver having a discharge opening therein, a means to regulate the transverse area of said opening to control the depth of material laid, roller means supporting said receiver above the ground and free of the opening therein, and a platform longitudinally of the receiver and above the surface of the material laid.

- In testimony whereof I have set my hand.

MARK M. BUTLER.
